UNITED STATES PATENT OFFICE

JOHN JACOB KAUFMANN, OF ELKINS PARK, AND LOUIS KASPER, OF PHILADELPHIA, PENNSYLVANIA, ASSIGNORS TO STEEL HEDDLE MANUFACTURING COMPANY, OF PHILADELPHIA, PENNSYLVANIA, A CORPORATION OF PENNSYLVANIA

HEDDLE FRAME

Application filed May 9, 1928. Serial No. 276,215.

Our invention relates to heddle frames for looms, and it relates more particularly to improved means for strengthening and stiffening the top and bottom rails of the frame intermediate the ends thereof.

The principal object of our present invention is to provide an improved form of stay or brace extending between the top and bottom rails of the frame which will effectually prevent springing of the frame, thereby insuring freedom and easy play of the heddles on the heddle bars.

A further object of our invention is to provide an improved form of stay or brace which can be readily and conveniently mounted in and detached from the frame, whereby certain of the heddles may, when required, be easily shifted from one side to the other of the stay rod, to the end that the same may at all times be properly arranged in the frame.

The nature and characteristic features of our invention will be more readily understood from the following description, taken in connection with the accompanying drawings forming part hereof, in which:

Figure 1 is a front elevation of a heddle frame provided with a stay or brace embodying the main features of our present invention;

Fig. 2 is an enlarged fragmentary detail view, partly in elevation and partly in section, illustrating the manner of connecting the stay rod to the top and bottom rails of the frame;

Fig. 3 is a transverse section thereof, taken approximately on the line 3—3 of Fig. 2, certain portions being shown in elevation;

Fig. 4 is a perspective view of a plate member provided with a spring tongue, the same constituting a portion of the device for locking the stay rod in the operative position; and

Fig. 5 is a perspective view of one end of the stay rod.

Referring to the drawings, in the particular embodiment of our invention therein shown, the heddle frame there shown comprises top and bottom rails 6, usually made

55 ends by means of end straps 7. Extending from end to end of the heddle frame, and arranged near the top and bottom rails thereof in the usual manner, are the heddle bars 8, upon which the heddles 9 are mounted and supported.

The stay rod proper comprises a thin, flat strip of metal 10, one or more of these being provided, and suitably located in the heddle frame at desired places intermediate the ends thereof. Each end of the stay rod 10 is provided with an aperture 11, which is adapted to be engaged by the horizontally extending portion 12 of a hook member 13 mounted in each of the rails 6, preferably 60 by means of a screw threaded portion 14.

65 Mounted on the inner edge of each of the rails 6, and secured thereto, preferably by means of screws 15, is a plate member 16. The plate member 16 is provided with a 70 spring tongue 17, which may be formed by striking the same out from the body portion of the plate member 16. The plate member 16 is apertured beyond the end of the tongue portion 17, and through this aperture the 75 hook member 13 extends. It will be noted that the free end of the spring tongue extends under the horizontal extension 12 of the hook member 13.

78 The arrangement is such that when the hook member 13 and the plate member 16 are mounted in the rail 6, the end of the tongue portion 17 of the plate member 16 will bear against the under side of the horizontal extension 12 of the hook member 13, and will 85 serve to retain the end of the stay rod 10 in its operative engagement with the hook member 13.

88 The stay rod 10 may also be provided with suitably located recesses 19 for the reception of the heddle bars 8, each recess 19 having an enlarged opening 20 for the engagement and disengagement of the heddle bar.

93 The hook members 13 and the plate members 16 are fixedly secured with respect to the 95 rails 6 in the manner hereinbefore described, and are not ordinarily removed therefrom after once being positioned thereon.

98 It is, however, well known that where intermediate stay or brace members are used 100

in heddle frames, it is frequently necessary to shift some of the heddles upon the heddle bars from one side to the other of the stay rod, in order to secure an even arrangement of the warp ends in the weave, and for this reason it is desirable that the stay rods be more or less easily removable and replaceable when desired.

When the stay rod is being mounted in the frame, the aperture 11 at one end of the rod is brought into engagement with one of the hook members, the spring tongue of the plate member being depressed until the end of the stay rod is positioned upon the horizontal extension 12 of the hook member 13 a sufficient distance, after which the end of the spring tongue 17 will serve to retain the end of the stay rod 10 upon the hook member.

When it is desired to remove the stay rod from the hook member, the spring tongue 17 is manually depressed, thereby permitting the stay rod to be removed from the hook member.

It will be seen that there is thus provided an arrangement for mounting the stay rods in heddle frames which may be inexpensively constructed, and which permits the stay rod to be mounted and dismounted with respect to the frame in a convenient and expeditious manner when required.

Having thus described the nature and characteristic features of our invention, what we claim as new and desire to secure by Letters Patent, is:

1. In a heddle frame, the combination of top and bottom rails, hook members mounted in the top and bottom rails, a stay rod having its ends apertured to engage the hook members, and devices having depressible spring tongues extending under the hook members and adapted to maintain the stay rod normally thereon.

2. In a heddle frame, the combination of top and bottom rails, hook members mounted in the top and bottom rails, a stay rod having its ends apertured to engage the hook members, and plate members secured to the top and bottom rails, each of said plate members having a depressible spring tongue, said spring tongues extending under the hook members and adapted to maintain the stay rod normally thereon.

3. In a heddle frame, the combination of top and bottom rails, heddle supporting rods, hook members mounted in the top and bottom rails, a stay rod having its ends apertured to engage the hook members, and plate members secured to the top and bottom rails, each of said plate members having a depressible spring tongue, said spring tongues extending under the hook members and adapted to maintain the stay rod normally thereon, and the stay rod having recesses in which the heddle bars are positioned and supported.

4. In a heddle frame, the combination of

top and bottom rails, heddle supporting rods, hook members in threaded engagement with the top and bottom rails, a stay rod having its ends apertured to engage the hook members, and plate members secured to the top and bottom rails, each of said plate members having a depressible spring tongue, said spring tongues extending under the hook members and adapted to maintain the stay rod normally thereon, and the stay rod having recesses in which the heddle bars are positioned and supported.

5. In a heddle frame, the combination of top and bottom rails, a stay rod extending therebetween, members carried by the top and bottom rails adapted to be detachably engaged by the ends of the stay rod, and devices having tongues normally engaging the ends of the stay rod to maintain the same in engagement with the aforesaid members carried by the top and bottom rails, said tongues being depressible to free the ends of the stay rods.

In testimony whereof, we have hereunto signed our names.

JOHN JACOB KAUFMANN.
LOUIS KASPER.
